FIG. 3 is a top view of the access-resistant holder of FIG. 1. FIG. 4 is a first side view of the access-resistant holder of FIG. 1.

FIG. 5 is a second side view of the access-resistant holder of FIG. 1.

FIG. 6 is a bottom view of the access-resistant holder of FIG. 1.

FIG. 7 is a third side view of the access-resistant holder of FIG. 1.

FIG. 8 is a fourth side view of the access-resistant holder of FIG. 1.

FIG. 9 is a top perspective view of an access-resistant holder in a closed condition in accordance with a first embodiment of the present teachings.

FIG. 10 is a bottom perspective view of the access-resistant holder of FIG. 9.

FIG. 11 is a top view of the access-resistant holder of FIG. 9.

FIG. 12 is a first side view of the access-resistant holder of FIG. 9.

FIG. 13 is a bottom view of the access-resistant holder of FIG. 9.

FIG. 14 is a second side view of the access-resistant holder of FIG. 9.

FIG. 15 is a third side view of the access-resistant holder of FIG. 9.

FIG. 16 is a fourth side view of the access-resistant holder of FIG. 9.

FIG. 17 is a top perspective view of an access-resistant holder in an open condition in accordance with a second embodiment of the present teachings.

FIG. 18 is a bottom perspective view of the access-resistant holder of FIG. 17.

FIG. 19 is a top view of the access-resistant holder of FIG. 17.

FIG. 20 is a first side view of the access-resistant holder of FIG. 17.

FIG. 21 is a second side view of the access-resistant holder of FIG. 17.

FIG. 22 is a bottom view of the access-resistant holder of FIG. 17.

FIG. 23 is a third side view of the access-resistant holder of FIG. 17.

FIG. 24 is a fourth side view of the access-resistant holder of FIG. 17.

FIG. 25 is a top perspective view of an access-resistant holder in a closed condition in accordance with a second embodiment of the present teachings.

FIG. 26 is a bottom perspective view of the access-resistant holder of FIG. 25.

FIG. 27 is a top view of the access-resistant holder of FIG. 25.

FIG. 28 is a first side view of the access-resistant holder of FIG. 25.

FIG. 29 is a bottom view of the access-resistant holder of FIG. 25.

FIG. 30 is a second side view of the access-resistant holder of FIG. 25.

FIG. 31 is a third side view of the access-resistant holder of FIG. 25.

FIG. 32 is a fourth side view of the access-resistant holder of FIG. 25.

FIG. 33 is a top perspective view of an access-resistant holder in an open condition in accordance with a third embodiment of the present teachings.

FIG. 34 is a bottom perspective view of the access-resistant holder of FIG. 33.
